(57) **CLAIM**

The ornamental design for a portion of display screen having graphical user interface with transitional icon, as shown and described.

DESCRIPTION

FIG. 1 is a front view of a portion of display screen having graphical user interface with transitional icon, showing our new design, according to a first embodiment and illustrating a first image thereof;

FIG. 2 is a front view of a second image thereof;

FIG. 3 is a front view of a third image thereof;

FIG. 4 is a front view of a portion of display screen having graphical user interface with transitional icon, according to a second embodiment and illustrating a first image thereof;

FIG. 5 is a front view of a second image thereof;

FIG. 6 is a front view of a third image thereof;

FIG. 7 is a front view of a portion of display screen having graphical user interface with transitional icon, according to a third embodiment and illustrating a first image thereof;

FIG. 8 is a front view of a second image thereof;

FIG. 9 is a front view of a third image thereof;

FIG. 10 is a front view of a portion of display screen having graphical user interface with transitional icon, according to a fourth embodiment and illustrating a first image thereof;

FIG. 11 is a front view of a second image thereof;

FIG. 12 is a front view of a third image thereof;

FIG. 13 is a front view of a portion of display screen having graphical user interface with transitional icon, according to a fifth embodiment and illustrating a first image thereof;

FIG. 14 is a front view of a second image thereof; and,

FIG. 15 is a front view of a third image thereof.

The appearance of the transitional icon in the graphical user interface sequentially transitions among the images shown in FIGS. 1-3, among the images shown in FIGS. 4-6, among the images shown in FIGS. 7-9, among the images shown in FIGS. 10-12, or among the images shown in 13-15. The process or period in which any image transitions to another image forms no part of the claimed design. Subject matter shown in broken lines is environmental and forms no part of the claimed design.
